CLAIM

I claim the ornamental design for the combination exercise and massage machine, as shown and described.

DESCRIPTION

FIG. 1 is a top perspective view of a combination exercise and massage machine incorporating my new design.

FIG. 2 is a back perspective view thereof.

FIG. 3 is a bottom perspective view thereof.

FIG. 4 is a front perspective view thereof.

FIG. 5 is a right side perspective view thereof.

FIG. 6 is a perspective view thereof; and,

FIG. 7 is a left side perspective view thereof.
